United States Patent Office

Des. 216,144
Patented Nov. 25, 1969

216,144

JACK

Martin L. Gillen, Hialeah, Fla.
(17941 NE. 9th Court, North Miami Beach, Fla. 33125)

Filed Dec. 16, 1968, Ser. No. 14,983

Term of patent 14 years

Int. Cl. D12—05

U.S. Cl. D41—1

FIGURE 1 is a right side elevation view of a jack;
FIGURE 2 is a front elevation view;
FIGURE 3 is a left side elevation view;
FIGURE 4 is a rear elevation view; and
FIGURE 5 is an end view which is the same as seen
from either end of the jack.

I claim:

The ornamental design for a jack, as shown and de-
scribed.
